LINT TRAP FOR CLOTHES DRYERS

Edward F. Woodland, Youngstown, Ohio

Application February 4, 1957, Serial No. 638,150

5 Claims. (Cl. 261—121)

This invention relates to a lint trap and more particularly to a construction which may be attached to a domestic clothes dryer to receive and trap lint and moisture discharged therefrom.

The principal object of the invention is the provision of a lint and moisture trap for attachment to a clothes dryer.

A further object of the invention is the provision of a lint and moisture trap that incorporates a readily removable lint and moisture vessel.

A still further object of the invention is the provision of a lint trap construction that may be mounted in a small space adjacent a clothes dryer.

A still further object of the invention is the provision of a lint and moisture trap for a clothes dryer that will effectively separate lint and moisture from warm, moist, lint laden air discharged by a clothes dryer and contain said lint and moisture while freeing said air.

The lint and moisture trap disclosed herein comprises a device which is attachable to a clothes dryer such as commonly used in drying articles of wearing apparel and the like under a forced draft of heated air. It is known in the art that such dryers commonly revolve the articles to be dried in a perforated drum through which heated air is directed. The lint from clothing, linens and the like is thereby entrained in the air along with the moisture being removed and is usually discharged into the atmosphere on the exterior of the dryer.

The present invention relates to a device attachable to such dryers so that the lint primarily, and, secondly, the moisture may be removed therefrom before the air is released into the atmosphere. Such an action is particularly desirable when the dryer is vented into the laundry room or other portion of an apartment house or dwelling in which the dryer is located.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a perspective view of the lint trap for clothes dryers.

Figure 2 is a vertical section taken on line 2—2 of Figure 1.

By referring to the drawing and Figure 1 in particular it will be seen that the lint trap for clothes dryers comprises a rectangular housing 10 having an open top and an integral bottom 11. A plurality of legs 12—12 support the housing 10 in elevated relation to a supporting surface such as a floor, and the legs 12—12 may obviously be adjustably mounted on the housing 10 so that the

2

respective heights of the housing 10 and the clothes dryer may be equalized.

The housing 10 has an opening 13 in one end thereof adjacent the bottom 11 and a rectangular tank 14 is disposed in said opening longitudinally of said housing and rests on the bottom 11. The rectangular tank 14 includes a bottom portion 15 and upstanding side and end walls of equal height with the exception that an end wall 16 is of slightly greater height so that it acts to close the opening 13 in the housing 10 when the tank 14 is installed therein.

By referring to Figure 2 of the drawing it will be observed that the top of the tank 14 is open so that a pipe 17 may be positioned with a portion of its lower end extending partially therein with the lower end 18 of the pipe 17 lying just below the hot water level in the tank. The pipe 17 is provided with an elbow at its uppermost end and the elbow is rotatably engaged on a nipple 19 which is positioned in and extends through an opening 20 in the housing 10 so that a portion of the nipple 19 extends exteriorly of the housing 10 as well as interiorly thereof. A clothes dryer, shown in broken lines and indicated by the letter D, is arranged with a discharge or a vent V adjacent the nipple 19 and may be connected thereto so that the warm moist lint laden air from the dryer discharged through the vent V thereof will be directed into the pipe 17 from which it will travel downwardly into the water in the tank 14 where the lint and excess moisture will be trapped and the remaining moisture will bubble up in the tank 14 and from which tank 14 it may escape through vents 21—21 in a top portion 22 which is engaged upon the upper open end of the housing 10.

The vents 21 are screened and at least one of them is formed in a cone shape so that if necessary additional water may be added to the tank 14 from time to time by simply pouring it through the cone-shaped vent 21.

In order that the water level may be maintained at or slightly above the plane of the lower end 18 of the pipe 17, a valved opening 23 is provided at the proper elevation on the end wall 16 of the tank 14 below a handle 24 thereon.

It will thus be seen that when the tank 14 is in the housing 10, as illustrated in Figures 1 and 2 of the drawing, and the pipe 17 is in vertical position, the device will operate for its intended purpose.

At such time as it is necessary to clean out the lint, the tank 14 may be slid out of the housing 10 whereupon the rear end wall thereof which extends above the lower end of the pipe 17, will engage the pipe 17 and swing it to angular position and permit the tank 14 to be completely removed. This swinging of the pipe will be repeated in reverse when the tank is replaced in the housing. Excess moisture in the tank 14 may be periodically or continuously drained by way of the valve opening 23 which controls the water level in the tank 14. It will occur to those skilled in the art that when the tank 14 is cleaned and replaced, it will be necessary to re-adjust the pipe 17 to vertical position.

It will thus be seen that a simple and efficient lint and moisture trap for a clothes dryer has been disclosed which meets the several objects of the invention.

Having thus described my invention, what I claim is:

1. A lint and moisture trap comprising a closed housing of substantial height, a removable liquid tank in the housing, the tank having a height materially less than the inside height of the housing and having an open top, air vent means in a wall of the housing at an elevation above the tank, inlet means leading into the housing through a wall thereof for conducting lint and moisture into the housing from a source of origin, a conduit in the housing leading downwardly from said inlet means

and terminating within and below the top of the tank for immersion in liquid contained in the tank, and means coupling the top end of said conduit with said inlet means permitting movement of the conduit relative to the tank whereby to facilitate withdrawal of the tank from the housing for cleaning and replacement of the tank in the housing.

2. The invention according to claim 1, wherein said tank includes a wall adapted to close an opening in a wall of the housing through which opening the tank is introduced into and withdrawn from the housing and a drainage means carried by said tank wall at an elevation at least as high as the working level of the lower end of said conduit in the tank.

3. The invention according to claim 1, wherein said inlet means comprises a short nipple having an inner end portion extending beyond the inside of the adjacent housing wall and an outer end portion extending beyond the outer side of said adjacent housing wall and the said coupling means between the top end of the conduit and the inlet means being a pivotal coupling with said inner end portion of the nipple.

4. The invention according to claim 3, wherein the pivot axis of said coupling extends perpendicularly to the line of movement of the tank in the withdrawal and replacement of the tank.

5. The invention according to claim 1, wherein the housing has a wall opening and said tank is located in

the housing in a position to be introduced thereinto and withdrawn therefrom through said wall opening, the said inlet means comprising a short nipple secured in an opening in and supported by a wall of the housing and having an end portion extending inwardly beyond the inside of the supporting wall in a direction substantially perpendicular to the line of movement of the tank in the operation of introducing the tank into and removing it from the housing, said conduit having a short right angularly extending elbow at its top end, and the said coupling means between the top end of the conduit and the inlet means consisting of a slip coupling between the end of said elbow and the said end portion of the nipple whereby the conduit is supported by the nipple for swinging movement about the axis of the nipple.
